UNITED STATES PATENT OFFICE

GEORGE C. DAVIS, OF CHICAGO, ILLINOIS, ASSIGNOR TO G. M. DAVIS REGULATOR COMPANY, OF CHICAGO, ILLINOIS, A CORPORATION OF ILLINOIS

STOP-COCKING VALVE

Application filed October 8, 1924. Serial No. 742,313.

My invention relates to improvements in stop cocking valves for use in connection with stop cocking or automatic self pumping oil wells and the like and it has for one object

5 to provide a new and improved form of stop cocking valve which can be set automatically to open when the pressure in the well reaches a predetermined point and to close when the pressure drops to a predetermined point. 10 Among the objects of my invention is the provision of a device which will open and close suddenly, thus making the change from a condition of flow and reduction of pressure to a condition of lack of flow and building up of 15 pressure and vice versa, sudden and complete.

It will be understood that such a valve as this is used in connection with oil wells where the pressure is not sufficient to cause the well to flow at all times but where the pressure if 20 entrained will gradually build up to a point at which sudden release will permit the pressure to blow out some of the oil, and my valve is intended to automatically open and close so that when the pressure has built up to a 25 point at which it will discharge oil from the well, the valve suddenly opens and the gas rushes out entraining with it oil, this continuing until the pressure drops to a point at which the gas can no longer discharge the oil, 30 when the valve automatically closes again to permit building up.

This condition can be produced in wells without gas pressure by introducing air under 35 pressure into the casing at a relatively low rate and allowing the air pressure to build up, then opening the valve automatically in the same way and allowing the air pressure to eject the oil. When this is done, it is necessary only 40 that the air pressure pipe be small enough so that during the time when the discharge valve is open to permit flow of oil, there will not be an unreasonable windage of the air, as it is most satisfactory to leave the air pressure 45 opening open at all times. Other objects will appear from time to time in the specification and claims.

My invention is illustrated more or less diagrammatically in the accompanying drawings, wherein—

The figure is a longitudinal section through the valve.

Like parts are indicated by like characters throughout.

A is a valve housing. Into it leads an intake pipe A¹. From it leads a discharge pipe A². A³ is the intake side of the valve and A⁴ the discharge side. These sides are separated by a closure or partition A⁵, having two opposed valve seat rings A⁶ A⁶ threaded in place and forming the valve ports. A⁷ A⁷ are valve discs joined by the central stem A⁸ and provided with guide fingers A⁹ adapted to center the discs in the seats while permitting free flow when the valves are open. A¹⁰ is a yoke associated with one of the discs A⁷.

Projecting upwardly from the yoke A¹⁰ and free to move laterally therein is a dumb-bell shaped connecting rod B free to move through predetermined limits with respect to a yoke 70 B¹. This yoke B¹ is pivoted on a hub B² and a coil spring B³ passes through the dumb-bell shaped connecting rod B and engages the top of one of the valve discs A⁷ at one end and the hub B² at the other end and is held under pressure to hold the parts yieldingly to prevent chattering and the like. B⁴ is a dash pot piston slidable in the cylinder B⁵ which projects outwardly from the housing A. This dash pot piston is provided with a packing ring B⁶ 80 held in place by the washer B⁷ and the hub B². B⁸ is a closure for the cylinder B⁵. It has an inwardly extending sleeve B⁹ terminating in a flange B¹⁰ extending out almost to the inner diameter of the plunger B⁴ so as to provide a 85 comparatively small annular passageway between the inner wall of the plunger and the outer periphery of the flange. B¹¹ is oil or suitable liquid material held within the cylinder and adapted to be expelled from between the 90 plunger and the collar or flange B¹⁰ when the plunger moves up. B¹² is a passage leading from the top of the cylinder B⁵ immediately below the cap B⁸ to a discharge pipe B¹³ surrounded by a housing B¹⁴, there being air 95 holes B¹⁵ leading out from the housing. This cylinder serves as a reservoir for the ejected oil when the plunger moves up and is arranged to permit the oil to drain back gradually when the plunger moves down.

C is a valve stem slidable in the sleeve B⁹ and extending out through the head B⁸. This stem is provided with a notch C¹ adapted to be engaged by a stop C² yieldingly pressed against the stem by a spring C³. C⁴ is a sear collar on the stem C. It is adapted to be engaged by a trigger C⁵ pressed outwardly against the stem and into engagement with the sear by the spring C⁶ in the pivot lever C⁷. C⁸ is a stop limiting the outward movement of the trigger under the urge of the spring C⁶. The lever C⁷ is pivoted on the pin C⁹ on a yoke C¹⁰ and it is provided at its outer end with a notch C¹¹ riding on a pin C¹².

D is a collar resting on the valve housing and surrounding the cylinder B⁵. D¹ is a lug projecting laterally therefrom and has pivoted thereon a socket D² in which is threaded a guide pin D³. This guide pin passes up through a block D⁴ which carries the pins C¹². D⁵ limits upwardly movement of the trunnion block and a spring D⁶ surrounds the pin D³ and is introduced between 25 the trunnion block and a collar D⁷. D⁸ is a nut threaded on the pin D³ adapted to adjust the position of the collar to adjust the tension of the spring. It will be understood that as pressure builds up in the intake side 30 of the valve and the plunger is moved up, the lever will be rotated, compressing the spring D⁶ until the pressure reaches a predetermined point at which time the spring will be sufficiently compressed to permit the 35 trigger to disengage from the sear, thus allowing the plunger to rise and carry with it the valve. The clearance between the port end of the dumb-bell shaped connecting rod B and the yoke B¹ permits this upward movement of the plunger to free the latch when 40 unseating the valve and it will be noted that the dumb-bell shaped connecting rod is long enough so that even if the latch or trigger has been free, the valve is not unseated until 45 the plunger is on its upward movement, thus adding the hammer blow of the moving parts of the plunger to the pressure thereof to positively unseat the valve.

E is a yoke projecting upwardly from the cylinder B⁵ carrying a spring housing E¹. This housing contains a spring E² compressed between the collar E³ on the upper end of the valve stem C and a collar E⁴ in the housing adapted to be downwardly adjusted by 55 means of a set screw E⁵.

When the trigger is released and the valve stem, plunger and valve travel up, the spring E² is compressed. The pressure and inertia of the parts is sufficient to move the valve 60 stem up until the ball stop C² engages the notch C¹ yieldingly locking the valve and associated parts in the upward position with the spring E² compressed. The compression of the spring E² is not sufficient when 65 the valve first opens to overcome the rela-

tively high pressure on the plunger but as the pressure gradually drops down, it would be possible for the low pressure spring E² to gradually move the plunger down and almost close the valve, though unless pressure 70 in the well dropped to atmospheric pressure, this spring would never be quite strong enough to seat the valve and therefore the spring latch is introduced. This spring latch holds the plunger up against the low pressure spring. When the pressure in the valve itself drops beyond a certain point, the low pressure spring which was not strong enough to overcome both the gas pressure and the latch pressure will be strong enough to overcome the latch pressure and will force the valve and its associated parts suddenly down, the inertia being sufficient to overcome the final pressure and seat the valve, thus making both opening and closing positive and sudden. On the down movement the sear collar engages the surface of the trigger, forces in the spring to permit passage downward of the sear.

The pressure at which the valve opens is 90 set by adjusting the high pressure spring D⁶. The pressure at which the valve closes is set by adjusting the low pressure spring E².

It will be evident that while I have shown 95 in my drawings an operative device, still many changes might be made in the size, shape and disposition of parts without departing materially from the spirit of my invention and I wish, therefore, that my showing be taken as in a sense diagrammatic. 100

I claim:

1. A stop cocking valve for oil wells and the like comprising a valve housing, a valve member therein, a control plunger exposed 105 on one side to the pressure in the valve housing, a connection between the plunger and the valve member, a yieldingly held stop for resisting the movement of the plunger and holding the valve member seated, the yielding stop holding means being adapted to permit the stop to release the plunger when the pressure on the plunger reaches a predetermined point, the connection between the plunger and the valve member being loose to 110 permit movement of the plunger and release of the stop before the valve member is lifted, yielding means interposed between the plunger and valve member tending to hold them in separated position.

2. The combination with a valve member and seat of a valve actuating element adapted 115 to engage the valve member directly to seat it, a tension member interposed between the valve actuating element and the valve member to permit the actuating member to unseat the valve, there being play in the tension member to permit the valve actuating member to move in the unseating direction before the valve responds to the unseating move- 120 125 130

ment, a trigger release for holding the valve actuating member in the closed position, the play between the actuating member and the connection being such that there is movement of the valve actuating member in the opening direction after the trigger has been released and before the valve commences to move from its seat.

3. A valve for stop cocking oil wells and the like comprising a housing, valve seat, a valve in opposition to said seat, a valve stem projecting outwardly through the housing, yielding means operating upon the valve stem tending to hold the valve in the seated position, a pivoted latch engaging the projection on the valve stem, yielding means for resisting rotation of the latch, said means being adapted when the pressure exerted by the valve stem exceeds a predetermined point to permit release of the stem and a connection between the valve and the valve stem whereby movement of the stem in opposition to the latch takes place without moving the valve previous to the release of the latch.

Signed at Chicago, county of Cook and State of Illinois, this 20th day of September, 1924.

GEORGE C. DAVIS.
